[57] CLAIM

The ornamental design for the end cap, as shown and described.

DESCRIPTION

FIG. 1 is a perspective view of one embodiment of the end cap, shown in use with the broken lines to indicate environment only and to form no part of the claimed design; FIG. 2 is a top plan view of the end cap shown in FIG. 1; FIG. 3 is a front elevational view of the end cap shown in FIG. 1, with the back side of the end cap being identical to that shown in FIG. 3;

FIG. 4 is a bottom plan view of the end cap shown in FIG. 1;

FIG. 5 is a left side elevational view of the end cap shown in FIG. 1, with the right side of the end cap being identical to that shown in FIG. 5;

FIG. 6 is a perspective view of a second embodiment of the end cap;

FIG. 7 is a top plan view of the end cap shown in FIG. 6; FIG. 8 is a front elevational view of the end cap shown in FIG. 6, with the back side of the end cap being identical to that shown in FIG. 8;

FIG. 9 is a bottom plan view of the end cap shown in FIG. 6; and,

FIG. 10 is a left side elevational view of the end cap shown in FIG. 6, with the right side of the end cap being identical to that shown in FIG. 10.
